UNITED STATES PATENT OFFICE.

MARY A. BYRNE, OF NEW YORK, N. Y.

TOILET-CASE.

SPECIFICATION forming part of Letters Patent No. 283,071, dated August 14, 1883.

Application filed May 24, 1883. (No model.)

To all whom it may concern:

Be it known that I, MARY A. BYRNE, of the city and State of New York, have invented an Improved Portable Toilet-Case, of which the following is a specification.

5 Pocket-books and bags of different kinds have been made with handles, so as to be convenient for ladies and others to carry suspended from the hand or finger, and shaving-cases have been provided with a glass inside of the lid, and with a stop-hinge or a strap, to limit the movement of the lid and to hold up the same in a convenient position for the glass to be used. My invention relates to a 10 toilet-case that is of a small size, adapted to be carried in the hand, and to contain chalk, powder, or other toilet articles, or a handkerchief, so that in traveling these articles are easily 15 accessible and add to the comfort of the person provided therewith.

The special feature of my improvement consists in combining with the toilet-case, having a looking-glass within the lid thereof, a flexible handle, by which the toilet-case can be 20 suspended from the hand, and which handle will also form a stay or support to keep the lid and mirror in nearly an upright position. This flexible handle is connected at one end to the bottom and at the other end to the lid 25 of the case, and causes the same to hang vertically, and tends to draw the two parts of the case together and lessen the risk of the same opening when being transported.

In the drawings, Figure 1 is a perspective 30 view of the case as open. Fig. 2 is a side

view, and Fig. 3 an edge view, of the case as closed.

The bottom *a* of the case is hinged at *b* to the top portion, *c*, and in this top portion or lid *c* there is a mirror, *d*. The case is preferably 40 covered or made of ornamental material—such as Russia leather, morocco, or plush—and of a convenient size to be carried in the hand.

The handle *e* is of flexible material, and one 45 end is fastened at *i* to the bottom *a* of the case, and the other end is fastened at *o* to the top or lid *c* of the case, and the length of this handle is such that where the case is open, as seen in Fig. 1, the lid and mirror will be supported 50 in a nearly vertical position, and when closed the handle is of a convenient length for suspending the case from the hand or finger, and the handle tends to draw the two parts of the case together; but I prefer to use a spring- 55 catch, as at *s*, to hold the lid to the bottom of the case.

I claim as my invention—

The combination, with the bottom *a* and lid *c*, of the hinge *b*, mirror *d*, and handle *e*, the 60 ends of which are connected with the bottom and lid, respectively, and form a stay to hold up the lid when the case is open, substantially as set forth.

Signed by me this 21st day of May, A. D. 65 1883.

MARY A. BYRNE.
